(57) **CLAIM**

The ornamental design for a frog-shaped keylight, as shown and described.

DESCRIPTION

FIG. 1 is a front elevational view of the frog-shaped keylight showing my design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken line showing is for illustrative purposes only and forms no part of the claimed design.

The diagonal lines applied to the circular mouth detail are shown to represent a transparent surface.
